UNITED STATES PATENT OFFICE.

JOHN H. WRIGHT AND BRUCE H. GROVE, OF BYRON, CALIFORNIA, ASSIGNEES OF ONE-TENTH TO ARTHUR E. MILLER, OF SACRAMENTO, CALIFORNIA, AND ONE-TENTH TO ASAPH WILDER, OF BYRON, CALIFORNIA.

GRADE-CROSSING ALARM.

Original application filed April 18, 1922, Serial No. 554,651. Divided and this application filed October 5, 1923. Serial No. 666,857.

To all whom it may concern:

Be it known that we, JOHN H. WRIGHT and BRUCE H. GROVE, citizens of the United States, residing at Byron, in the county of Contra Costa and State of California, have invented new and useful Improvements in Grade-Crossing Alarms, of which the following is a specification.

This invention relates to a grade crossing alarm of the type where a bell or light is caused to operate upon the approach of a train from either direction.

The principal object of this invention is to provide means whereby a visible or audible signal may be displayed upon the approach of a train, without upsetting the usual signalling systems, such as the block signals now employed on many railroads or a system as described in our co-pending application Serial Number 554,651, filed April 18, 1922, of which this is a divisional case.

Another object is to provide a signal which is extremely simple, cheap to install and one which will be automatic in operation.

A still further object is to provide means for maintaining the normal block signal system in operation, while the crossing signal is also being operated.

Other objects and advantages will be apparent during the course of the following description.

In the accompanying drawings forming a part of this specification, and in which like numerals are employed to designate like parts throughout the same,

In the drawing the view diagrammatically illustrates our invention.

Applicants are aware of the fact that many crossing signals are employed upon railroads, which crossing signals, however, require an expensive installation, while our installation is extremely simple and therefore cheap.

In the accompanying drawings wherein for the purpose of illustration is shown a preferred embodiment of our invention, the numeral 5 refers to a continuous railroad rail, while the numerals 6, 7 and 8 refer to rail sections, parallel spaced from the rail 5. These rail sections are insulated by insulating pieces 9 and 11.

A battery 12 has one side electrically con-

nected as shown at 13 to the rail 5 and has its opposite side electrically connected as 55 shown at 14 to the rail section 7. At 16 is located a relay magnet which is also electrically connected to the points 13 and 14. This magnet is adapted to normally hold the armature 17 out of contact with the contact 60 18. This contact 18 is electrically connected to a bulb 19 which is in series with a bell 21, the opposite side of which bell is connected to a battery 22.

This battery is, in turn, electrically connected to the armature 17 at the point 23. A similar electro-magnet 24 is connected in parallel with the magnet 16 and serves to normally hold the armature 26 out of contact with the contact 27. This armature 26 70 is electrically connected, as at 28, to a wire which is, in turn, connected to the rail 5.

As shown at 30, the contact 27 is electrically connected to a wire 31, the opposite ends of which wire are connected to the rail 75 sections 6 and 8 and thereby bridge the rail section 7.

The operation of our device is as follows:—

Assuming that a train is approaching the 80 grade crossing, the same, after passing the insulated portion 11, will short circuit the battery 12 thereby causing the electro-magnets 16 and 24 to allow their respective armatures 17 and 23 to contact the contacts 18 85 and 27. When the armature 17 and the contact 18 have contacted current will flow from the battery 22 through the light 19 and the bell 21, thus giving a visible and audible signal at the grade crossing. At the same 90 time the release of the armature 28 will allow the same to contact the contact 27, thus establishing a circuit between the rail 5 and section 6, thus holding the block signal in the block ahead, which would otherwise be 95 lost if no connection were made between the section 6 and rail 5.

It is of course understood that the rail section 7 is of considerable length on either side of the grade crossing. The section 7 100 of the track might be termed a neutral section as it has no function relative to the signalling apparatus.

It is to be understood that the form of our invention herewith shown and described is 105 to be taken as a preferred example of the

same and that various changes in the shape, size and arrangement of parts may be resorted to without departing from the spirit of the invention or the scope of the subjoined claim.

Having thus described our invention, we claim:—

In a device of the character described the combination with a continuous rail, a sectional rail parallel with said continuous rail, the sections of said sectional rail being insulated one from the other, an electro-magnet electrically connected to said continuous rail and one of the sections of said sectional rail, a battery connected to said continuous rail and one of the sections of said continuous rail, a second electro-magnet

connected in parallel to said first mentioned magnet, armatures pivoted adjacent each of said magnets, a bell and bulb connected in series, a contact connected to one side of said bulb and a battery connected to one side of said bell, said battery having its opposite side connected to one of said armatures, the other of said armatures being adapted to complete a circuit from said continuous rail to remote sections of said sectional rail, substantially as and for the purpose specified.

In testimony whereof we affix our signatures.

JOHN H. WRIGHT.
BRUCE H. GROVE.
